UNITED STATES PATENT OFFICE.

ADOLPH J. EILAU, OF CHICAGO, ILLINOIS.

MILLINER'S IRON.

1,102,399.

Specification of Letters Patent.

Patented July 7, 1914.

Application filed November 29, 1913. Serial No. 803,707.

To all whom it may concern:

Be it known that I, ADOLPH J. EILAU, a citizen of the United States, residing at Chicago, in the county of Cook and State of Illinois, have invented certain new and useful Improvements in Milliners' Irons, of which the following is a specification.

My invention relates to improvements in milliners' irons, the present embodiment being particularly designed and adapted to meet the demands of milliners in pressing the crowns and brims of hats, shaping, etc., and is adapted to be heated by electricity, gas, or some other suitable and convenient 15 heating medium.

The primary object of the invention is to provide a generally improved iron of this class, of exceedingly simple, cheap, and efficient construction for use in the art of hating for transmitting the heat to some portion of the hat body during the shaping or pressing of the same.

A further object is to improve the construction and arrangement of parts as well 25 as to adapt the main body portion of the iron to different forms of heating elements such as a gas burner, electric resistance coil, or the like.

A still further object is to provide improved 30 means for quickly and conveniently attaching the iron handle to or detaching the same from the body of the iron containing the heating element or unit.

With the above mentioned and other ends 35 in view, the invention consists in the novel construction, arrangement, and combination of parts, hereinafter described, illustrated in one of its embodiments in the accompanying drawings, and particularly pointed out 40 in the appended claims.

Referring to the drawings, forming a part of this specification Figure 1, is a perspective view of the improved iron in its assembled or operative position. Fig. 2, a vertical central sectional view through the iron body and the base or attaching portion of the handle arms. Fig. 3, a top plan view of the attaching or supporting disk plate adapted to support the heating element or unit, 45 for example a gas burner, electric resistance coil, or the like. Fig. 4, a detail view of the guide bracket for supporting the latching pin carried by the base or attaching portion of the handle. Fig. 5, a detail top plan view 50 of the handle bracket, the handle and latch-

ing pin being removed for the purpose of clearer illustration of the parts.

Similar numerals of reference designate like parts throughout all the figures of the drawings.

The improved iron comprises a main body portion 1, preferably of spherical or ball shape, and provided with an opening or receptacle 1^a, extending from the top and adapted to receive and contain the heating unit or element, in the present instance, in the form of an electric heating or resistance coil 1^b. The heating unit or resistance coil may be carried upon a supporting or attaching disk plate 2, which latter is adapted to 60 be secured by means of a plurality of screws 3. The screws 3, are threaded into the top of the body 1, and in the present instance, pass through a series of screw receiving notches 3^a, (see Fig. 3) arranged about the 65 periphery of the plate or cover 2.

The heater receptacle 1^a, is preferably provided at its mouth with an off-set portion 1^c, corresponding in thickness to the marginal edges of the cover or supporting plate 2, so that the latter will extend flush with the top of the cylindrical body 1, when in proper position as shown in Figs. 1 and 2, of the drawings.

The handle 4, is preferably of wood, or 80 other suitable non-conductor of heat, and is mounted between and connected to suitable brace or handle arms 5.

As a means for conveniently attaching the handle arms 5, to and detaching the same 85 from the body of the iron, the base portion 5^a, of the handle bracket is provided with openings 6, the latter being provided with slot extensions 6^a, and when it is desired to fasten the handle to the iron the openings 6, 9 are brought into registry with the screw heads 7, projecting above the plate or cover 2, and when the base portion 5^a, is seated upon the plate 2, the base portion is moved longitudinally thereby causing the slot extensions 6^a, to move underneath the screw heads 7, in a well known and understood manner.

As a means for latching the handle bracket in its secured position, the base portion 5^a, of the bracket is provided with an opening 5^b, adapted to be brought into registry with a second opening 2^a, in the disk or cover plate 2, and said base portion 5^a, is further provided with a guide bracket 8, extending 1

- above the opening 5^b, and provided with an opening receiving and containing a vertically movable latch pin 9, provided with a handle top 9^a. As a means for causing the latch pin 9, to be pressed downwardly the pin 9, is surrounded by a coil spring 10, one end of the latter being secured to the latch pin and the other abutting beneath the top of the guide bracket 8.
- 10 When it is desired to detach the handle from the body of the iron the latch pin 9, is raised against the resistance of the coil spring 10, through the medium of the handle top 9^a, after which the base portion 5^a, 15 of the handle bracket may be moved longitudinally to detach the same from the disk or cover plate 2, of the iron body.

From the foregoing description, taken in connection with the accompanying drawings, the advantages and operation of my invention will be readily understood.

Having thus described one of the embodiments of my invention, what I claim and desire to secure by Letters Patent is,—

- 25 1. A milliner's iron, comprising a ball-shaped body provided with a centrally located cylindrical shaped receptacle, the latter terminating at its mouth in an annu-

lar off-set portion, a supporting disk plate normally covering said receptacle and seated in said off-set portion, a heater element detachably carried on said disk plate and removably disposed within said receptacle, and a handle and handle bracket detachably connected to said disk plate. 30

2. A milliner's iron, comprising a ball-shaped body provided with a centrally located cylindrical-shaped receptacle terminating at one side of said body in a circular-shaped off-set portion, a circular-shaped supporting plate removably mounted within said circular-shaped off-set portion, a cylindrical-shaped heating unit detachably connected to said supporting disk plate and removably mounted within said cylindrical shaped receptacle, and a handle and handle bracket detachably connected to the top side of said supporting disk plate independently of said cylindrical shaped heating unit. 40

45 In testimony whereof I have affixed my signature in presence of two witnesses.

ADOLPH J. EILAU.
